UNITED STATES PATENT OFFICE.

JOHN WILLIAM SHUTE, OF IGERNA, CALIFORNIA.

CUFF-HOLDER.

SPECIFICATION forming part of Letters Patent No. 784,076, dated March 7, 1905.

Application filed February 23, 1904. Serial No. 194,858.

To all whom it may concern:

Be it known that I, JOHN WILLIAM SHUTE, a citizen of the United States, residing at Igerna, in the county of Siskiyou and State of California, have invented certain new and useful Improvements in Cuff-Holders, of which the following is a specification.

My invention relates to devices for holding detachable cuffs in proper position independently of the shirt-sleeves; and my object is to provide a simple, cheap, and effective device for such purpose which can be easily applied and removed. Such a device obviates the necessity of buttoning the cuffs to the sleeve, which with the heavily-starched cuffs generally worn is a difficult matter, and, moreover, gives the cuffs the proper length or degree of projection beyond the coat-sleeve, whereas with buttoned cuffs a shirt-sleeve which is too short will cause the cuff to be concealed, while one which is too long will cause the cuff to project too far, and so present an unsightly appearance and be uncomfortable in wear. Embodiments of my invention by which these objects are accomplished are shown in the accompanying drawings, in which—

Figure 1 is a view of a coat-sleeve broken away to show a cuff with my cuff-holder in position. Fig. 2 is a perspective view of the cuff-holder as formed from wire. Fig. 3 is a similar view of a cuff-holder formed from sheet metal. Fig. 4 is a modification of the cuff-holder shown in Fig. 3.

The device shown in Figs. 1 and 2 is my cuff-holder when made from a single piece of wire. The shank 1 is formed by twisting together the two arms of a length of wire bent upon itself, and an opening 2 is left in the twisted part. At one end of the shank the wire is separated and bent, so as to form two arms 3 3, which are substantially at right angles to the plane of the shank and at a proper angle to each other. The ends of these arms have feet 4, preferably formed by bending such ends around and upon themselves. At the front end of the cuff-holder the double

wire is bent upon itself, so as to form a tongue 5, and said tongue is provided with an inwardly-bent portion 6, which projects toward and preferably into the opening 2.

The manner of using the cuff-holder is clearly illustrated in Fig. 1. The arms 3 3 are thrust into two opposite buttonholes of the cuff from the outside and are there held by the enlarged ends or feet 4. The shank extends along the cuff to the front, and the forward bent end is slipped over the edge of the coat-sleeve, preferably on the lower side of the latter. As the bent part of the tongue projects toward the opening 2 the fabric of the sleeve is pressed into the opening and positively clamped at that point and there is no danger of the attachment slipping, and the tongue can be connected to any point on the edge of the coat-sleeve or adjusted after attachment to any desired point. When properly placed, the tongue is practically concealed and when applied to the inner ply of sleeves overlapping at the edge is actually concealed. In any case, however, the tongue is inconspicuous and not unsightly.

The device shown in Fig. 3 is formed from sheet metal instead of wire; but in structure and function it is similar to the wire-holder already described. It can be cheaply formed by bending stamped blanks to the proper shape.

The modification shown in Fig. 4 is also a sheet-metal cuff-holder and differs from that shown in Fig. 3 only in substituting for the hole 2 a recess 2^a, formed by making a bend in the shank. This recess, in connection with the adjacent projection 6, acts a clamp for the fabric of the coat-sleeve in substantially the same way as the clamps of Figs. 1, 2, and 3.

Having thus described my invention, what I claim as new, and desire to secure by Letters Patent, is—

A cuff-holder comprising a shank having two arms projecting from it substantially at right angles and diverging from each other and adapted to be connected to opposite but-

tonholes of the cuff, and a tongue bent backwardly from the other end of said shank and adapted to engage with the edge of a coat-sleeve, a receiving-space in the shank, and a
5 projection on said tongue opposite the receiving-space whereby the material of the sleeve is clamped.

In testimony whereof I have affixed my signature, in presence of two witnesses, this 25th day of January, 1904.

JOHN WILLIAM SHUTE.
